UNITED STATES PATENT OFFICE.

ERNST ROTH, OF LAUTAWERK, GERMANY.

DISINTEGRATING MACHINE.

Application filed October 12, 1925, Serial No. 62,132, and in Germany November 1, 1924.

My invention relates to an improved disintegrating machine.

The machines of this type as hitherto constructed are objectionable for the reason that disintegration is effected therein by elements or means, which are either integral parts of the machine, such as walls, ribs and the like, or individual parts such as balls and the like, which are placed in the machine for concussive purposes. As these means or elements are subjected to heavy strains and stresses and therefore considerable wear they must necessarily be made of a hard material.

More particularly my invention refers to a disintegrating machine of the stated type, having a biconical casing composed of or constituted by two hollow conical parts disposed with their bases or flaring ends opposite each other and adapted to be revolved in opposed directions and the object of my invention is to overcome in a machine of this kind, the hereinbefore stated disadvantages.

With this object in view I provide on the inner surfaces of the two hollow conical parts or discs a number of radial ribs adapted to prevent the materials from moving over the said parts or discs, and to only guide the materials towards and into the working zone of the machine. This zone is situated in the vicinity of and between the base surfaces of the two conical parts or discs, and the material is guided into this zone from both sides through the agency of the stated radial ribs, so that the material supplied by the one disc will meet with the material supplied by the other disc, with the result that the particles will rub against each other and be reduced to powder owing to the mutual rubbing or grinding action of the particles themselves, due to the centrifugal action and the opposed rotary motion imparted by the two conical discs, constituting the casing.

It will be seen that the radial ribs act to feed the material, under the action of centrifugal force, towards the bases or flaring ends of the two conical discs, while rotating together with and at the same speed as the conical parts of the casing, so that the disintegration of the material mainly occurs in the above mentioned base-zone where the particles meet, whilst being revolved with great speed in opposed directions, by way of the highly intensive self-rubbing action result-

ing from the peculiar motion imparted to the particles.

As the material is prevented by the said ribs from moving freely all over and about the inner surfaces of the two hollow conical discs, the latter do not partake in the disintegrating action and, therefore are not subjected to wear, so that they may be made or consist of any less expensive material, such as ordinary grey cast-iron.

The casing is revolved with very high speed so that heavy centrifugal forces are produced therein. In order to obviate the destructive tendencies of such forces reinforcing rings are provided in or near the base edge or periphery of each individual disc and preferably the reinforcing rings are mounted on the discs in a manner to allow of ready exchange. Between the opposed base edges of the two conical discs or, in case of equipping the same with reinforcing rings, between the two rings an annular slit or gap is arranged for the pulverized material to escape from the casing and an annular channel or trough round about the slit or gap for the reception of the pulverized material and for conveying the same to a point preferably near the lower end of the casing.

With the above recited object in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms, in which the claims are expressed.

The accompanying drawings, forming a part of this specification, show for purpose of exemplification two preferred forms and manners, in which the invention may be embodied and practised:

Figure 1 is a diagrammatic view in longitudinal section of the machine partly broken off and having a hollow shaft both for the transmission of rotary movement and for the supply of material to the casing;

Figure 2 is a similar view of a modification including a supplying or charging hopper and a solid shaft, only one half of the casing being shown;

Figure 3 is an end view thereof with a por-

tion of the hollow conical disc broken away. In the embodiment shown in Figure 1 the machine comprises a casing constituted by two independent hollow conical discs a^1 and a^2 located with their flaring base ends or peripheral edges towards and in the close vicinity of each other and having each a number of radial ribs b^1 and b^2 , respectively. The peripheral base or edge surface of the disc a^1 and a^2 , is grooved and exchangeable reinforcing rings c^1 or c^2 , are inserted into the groove, so that a small gap or slit s will remain to separate the discs a^1 and a^2 from each other. Each disc is rigidly connected with a hollow shaft d^1 and d^2 respectively, so as to communicate with the latter. The connection of the parts may be effected by means of annular flanges f^1 and f^2 at the ends of the shafts and with the aid of bolts, not shown. Each shaft d^1 and d^2 is supported in suitable bearings h^1 , i^1 and h^2 , i^2 , respectively, and equipped with a belt pulley g^1 and g^2 , respectively, of usual construction for the driving purpose. A conveying screw e^1 and e^2 is provided in each hollow shaft d^1 and d^2 , respectively for supplying the material to the casing.

As above stated an annular channel or trough is to be provided for the reception of the pulverized material, escaping through the slit or gap s and for conveying the same to a container of any suitable shape. This annular trough is not shown in the drawings, because it may be of any appropriate construction and arrangement known in the art, so that those, to whom this specification is addressed, will readily understand the shape and disposition of these subordinate means, although the latter are not shown.

40 The operation is as follows:

The material, e. g. bauxite, to be disintegrated, is supplied in any suitable manner to the hollow shafts d^1 and d^2 , and the conveying screws e^1 and e^2 , which are driven by any appropriate means, not shown, act to slowly feed the material towards and into the biconical casing. The two pulleys g^1 and g^2 are driven to revolve in opposite directions at a speed of say 3000 revolutions per minute. Upon entering the casing the material is prevented by the ribs b^1 and b^2 from following the revolutions of the casing, but is conveyed by the ribs, under the action of the progressively increasing centrifugal force, from the apices of the two conical discs towards the flaring bases thereof, that is to say towards the peripheral portion of the casing or the working zone of the machine which, as hereinbefore mentioned, lies in the vicinity of and between the opposed base parts of the two conical discs. In this zone the particles of the material supplied by the two revolving discs meet and, as they are revolved with the high speed, at which the machine runs, they are reduced to a powder,

owing to the rubbing action between each other, which they incessantly undergo. It will be seen that the walls of the casing and the ribs provided therein merely are containing and guiding members and have nothing to do with the disintegrating action, properly speaking, since the latter is only effected by the material itself and the parts constituting the casing do not partake in the disintegrating action.

75 In the modification of the machine illustrated in Figures 2 and 3 the material is supplied to each hollow disc through a hopper or funnel, so that the hollow shaft and the conveying screws may be dispensed with and a solid shaft is employed. In this embodiment some of the radial ribs are shaped and arranged to support the conical discs. To this end they are elongated, extend inwards to form a hub keyed to the shaft and preferably the disc, the guiding ribs, the supporting ribs and the hub are cast integral with each other to form a unit. In the embodiment shown there are three supporting ribs 80 symmetrically arranged at a distance of 120° apart from each other. The supplying hopper or funnel is arranged to discharge its contents into the cylindrical space thus formed, the arrangement being such that the hopper or funnel discharges in the direction, 85 in which the hollow conical disc is driven to revolve.

90 As will be seen in Figures 2 and 3 the hollow, conical disc A, the guiding ribs R, the supporting ribs B and the hub C are 100 firmly connected to the solid shaft W by means of a key, not shown. The funnel or hopper D is shaped to form a sloping tube E with its mouth projecting into the free cylindrical space F of the conical disc, so that the material to be disintegrated will be 105 discharged into the space F and thence travel into the several guiding sections formed by the guiding ribs R and also ribs B in order to be guided in radial direction to the peripheral part of the conical disc and to meet the material supplied and guided in the same manner in the counter-disc, not shown for the disintegrating purpose, as described hereinbefore with reference to the embodiment 110 illustrated in Figure 1.

115 From the foregoing description, it will be seen that simple and efficient means are herein provided for accomplishing the object of the invention, and it is believed that the advantages and novel features of my invention will be readily understood and, therefore, further detailed description is deemed unnecessary.

120 What I claim is:

1. A disintegrating machine, comprising a casing composed of two hollow, conical discs, a shaft duly supported and rigidly connected with the one disc, a second shaft duly 125

- supported and rigidly connected with the other disc, means for revolving the two shafts together with their discs in opposed directions, and radial ribs in the said conical discs, 5 the arrangement being such that the flaring ends of the two conical discs are opposite and adjacent to each other with a small annular gap or slit therebetween.
2. A disintegrating machine, comprising a 10 casing composed of two hollow, conical discs, a shaft duly supported and rigidly connected with the one disc, a second shaft duly supported and rigidly connected with the other disc, means for revolving the two shafts together with their discs separately in opposed 15 directions, radial ribs in the said conical discs, and reinforcing rings on the two conical discs arranged with their flaring ends opposed each other, so as to leave a small annular gap 20 or slit therebetween.
3. A disintegrating machine, comprising a casing composed of two hollow, conical discs, a shaft duly supported and rigidly connected with the one disc, a second shaft duly supported and rigidly connected with the other disc, means for revolving the two shafts together with their discs separately in opposite 25 directions, radial ribs in the said, conical discs, which are arranged with their flaring ends 30 adjacent to and opposite each other so as to leave an annular gap therebetween and exchangeable reinforcing rings inserted into the said two conical discs and an annular slit therebetween.
- 35 4. A disintegrating machine comprising a casing composed of two hollow, conical discs, a shaft duly supported and firmly connected with the one disc, a second shaft duly supported and firmly connected with the other disc, means for revolving the two shafts together with their discs separately in opposite 40 directions, radial guiding ribs in the said
- disks partly elongated to meet and form a hub for the connection between the conical disc and its shaft, and a separate charging 45 hopper in connection with each conical disc, the arrangement being such that the flaring ends of the two conical discs are opposite and adjacent to each other with an annular gap 50 therebetween.
5. A disintegrating machine, comprising a casing composed of two hollow conical discs, a shaft duly supported and rigidly attached to the one disc, a second shaft duly supported and firmly attached to the other disc, means 55 for revolving the two shafts together with their discs separately in opposite directions, radial guiding ribs in the said hollow discs partly elongated to meet and form a hub for the connection between the conical disc and its shaft, a separate charging hopper in connection with each conical disc, and reinforcing 60 rings on the two conical discs arranged with their flaring ends opposite each other so as to leave an annular slit therebetween. 65
6. A disintegrating machine, comprising a casing composed of two hollow, conical discs arranged with their free flaring ends, adjacent to and opposite each other with an annular slit therebetween, a hollow shaft duly 70 supported and rigidly connected with the one disc for communication therewith, a second hollow shaft duly supported and rigidly connected with the other shaft for communication therewith, means for revolving the two 75 hollow shafts with their discs separately in opposite directions, radial ribs in the said two conical discs, reinforcing rings at the flaring ends thereof, and conveying screws in the said hollow shafts, substantially as and 80 for the purpose set forth.

In witness whereof I affix my signature.

ERNST ROTH.
